OVERCOAT

Conrad B. Shane, Wilmette, Ill., assignor to C. B. Shane Corporation, Chicago, Ill., a corporation of Illinois

Application February 11, 1936, Serial No. 63,382

3 Claims. (Cl. 2—97)

This invention relates to an outer garment, such as a topcoat or overcoat. The present improvements have to do with the construction of such a garment by which it may be fitted with a lining 5 removably held in place by hook fasteners. The principal object of my invention is to so arrange and reinforce the several parts entering into the garment construction as to successfully withstand the tendency of such metallic fasteners to produce a distortion or mal-fitting of the garment when in use.

At the present time topcoats and overcoats having a removable lining secured in place by hook fasteners have attained considerable popularity. 15 The use of such fasteners, however, involves an appreciable extra weight which is concentrated along a single line where the cooperating rows of fasteners are placed. The result is a tendency for the garment to hang badly, to refuse a smooth and perfect fit, and quickly to acquire a bulge or distortion which spoils the appearance of the garment. It is with a view to overcoming such deficiencies that the present improvements have been devised.

25 An exemplification of this invention is set forth in the accompanying drawing wherein—

Figure 1 is a view of an overcoat or topcoat, looking toward the inside, and showing the full lining therein partly removed;

30 Fig. 2 which is a fragmentary view shows one of the garment fronts with a portion thereof broken away to exhibit the canvas front to the inside thereof; and

35 Figs. 3 and 4 are details in section, on an enlarged scale, taken on lines 3—3 and 4—4, respectively, of Fig. 1.

The present topcoat and overcoat which is made from suitable fabric material, comprises opposed fronts 4 each having an associated facing 5 which 40 may extend for the full length of the garment, as is customary.

45 Between each front and facing is interposed a canvas front comprising, by preference, a sheet 6 of padding and another 7 of canvas. Each canvas front extends from a point adjacent the shoulder down along the facing well toward the bottom of the garment. It may be secured to both the fabric front and associated facing as by 50 a line of stitching 8 adjacent the free edge of the front, and by a second line of stitching 9 (see Fig. 2) near its upper edge in the shoulder region. The canvas front is also secured as by an additional line of stitching 10 which connects with the 55 facing only, this latter connection passing through

a part lining 11 which underlies the inner edge portion of the facing.

The connection line 10 which extends downwardly from the shoulder region for a substantial distance lies inwardly of the facing edge 12 which 5 is remote from the free edge of the garment front. As by other connections 13 the facing is secured to a tape 14 which is attached invisibly to the front along a line which lies inwardly of the facing edge 12. The portion of the facing which is thus 10 free forms in effect a flap to the under side of which is secured, as by two rows 15 of stitching, a tape 16 which carries a row of metallic hook fasteners 17. This row of fasteners, it will be noted, lies beneath the flap so as to be concealed 15 from view, and also relatively close to the stitching line 10 which connects the facing to the canvas front in the upper region of the garment.

The garment full lining 18 is equipped around 20 its edges (except the bottom) with a row of complementary hook fasteners 19 adapted to interengage the row of fasteners 17 in response to operations of a slide 20. The present garment will, of course, be constructed with the usual arm holes, sleeves, collar, pockets, and other desired features, 25 with none of which this invention is especially concerned.

In use, the rows of interengaging hooks which are disposed in the region of the garment fronts impose an appreciable weight which is confined 30 to a single line that lies close to the line of stitching 10 that connects only with the reinforcing canvas front. This reinforcement hangs from the shoulder to which it is also secured by a line 35 of stitching, and the result of such upper and longitudinal supports is a smooth and perfect fitting of the garment. The full and unwrinkled appearance that comes from the presence of the canvas front is in nowise impaired or affected by the concentrated load imposed by the metallic 40 fasteners. In this construction I have added no extra parts, nor have I in any way bulged out the construction of the garment, but have retained only the usual elements which are necessary and desirable for its correct fitting and satisfactory 45 service.

In the preceding description I have referred to connections of stitching which are common at the present time, but obviously any other form of connection which is equally serviceable might be 50 substituted. The essence of this invention appears to be the use of a garment reinforcement in the nature of a canvas front having a connection, closely adjacent the row of metallic fasteners for a substantial distance in the upper 55

region thereof, with the garment facing in a manner which relieves the fabric front of the garment from sustaining any appreciable part of the load imposed by fasteners of this character.

5 I claim:

1. In an overcoat, the combination with two fabric fronts having associated facings extending up from points adjacent the garment bottom and around the shoulders, the inner edge portion of the facing being free whereby to provide a flap, a row of hook fasteners secured beneath the flap and extending continuously therewith from a point adjacent the bottom of one facing, 10 up across the shoulders, and back again to a point adjacent the bottom of the other facing, canvas fronts between the fabric fronts and facings, each extending from a line adjacent the shoulder downwardly well toward the bottom of the associated facing, a line of stitching connecting each canvas front to the proximate fabric front and facing along its top edge, another line of stitching connecting each canvas front only to the facing parallel to the inner edge of the flap, 15 a lining upon the inside of the coat having its edges adjacent the row of hook fasteners and itself provided with a complementary row of hook fasteners, and a slide fastener operable to removably join both rows of hook fasteners whereby 20 to secure the lining in place.

2. In an overcoat, the combination with two

fabric fronts having associated facings each facing being secured at points removed from its inner edge whereby to provide a flap, a row of hook fasteners affixed beneath each flap close to the points of securement, a canvas reinforcement between each front and facing extending downwardly from a point adjacent the shoulder and secured to both the front and facing adjacent its top edge and to the facing alone for a substantial distance adjacent the points of securement of the facing, a lining having a row of hook fasteners complementary to those beneath the flaps of the garment, and a slide fastener operable to removably join both rows of hook fasteners whereby to secure the lining in place. 15

3. In an overcoat, the combination with two fabric fronts having associated facings, a row of hook fasteners affixed to each facing and extending continuously therebetween, a canvas reinforcement between each front and facing extending downwardly from a point adjacent the shoulder and secured to both the front and facing adjacent its top edge and to the facing alone in proximity to the row of fasteners carried thereby for a substantial distance, a lining having a 20 row of hook fasteners complementary to those on the facing, and a slide fastener operable to removably join both rows of hook fasteners whereby to secure the lining in place. 25
